[57] ABSTRACT

A prefabrication installation is provided for moulded elements of concrete or other materials, each element having two opposite end faces, the elements being adapted to be disposed consecutively one after another and assembled together to form an assembly in which each element of the series engages by one of its end faces with the adjacent end face of an immediately adjacent element of the series. The installation comprises, for moulding an element of the series, a mould bounded at one end by that one of the end faces of the previous already moulded element against which the finished element will subsequently be engaged when the elements are positioned in a series or row. The mould also comprises formwork extending lengthwise of the element to be moulded between the two end faces thereof, such that the formwork bears on the previous already moulded element by way of at least one locating element co-operating with a complementarily shaped locating portion in the immediately previous element. Means are provided for predetermined the position of the locating portion in dependence upon the pattern of the required assembly and of the subsequent position therein of the element being moulded.

PROGRESSIVE MOLDING APPARATUS WITH ADJUSTABLE LOCATING MEANS

This invention relates to a prefabrication installation for moulding elements of concrete or the like materials, each element having two opposite end faces, the moulded elements being adapted to be subsequently assembled together to form longitudinally-consecutive sections of a civil engineering work in which each element in the work abuts by one of its end faces with the adjacent end face of an immediately adjacent element in the work.

Such elements can be, for example, voussoirs for use in building bridges or elevated highways or else they can be sections of pipes or else they can be slabs, roof elements and so on, the list not being exhaustive.

The invention relates more particularly to a prefabrication installation comprising, for moulding a new or fresh element, a mould projecting beyond that one of the end faces of the immediately previous, already moulded element against which the new element will subsequently abut when the elements are assembled in the work, the mould including a main longitudinal shutting extending lengthwise of the element to be moulded.

Consequently, when the moulded elements are subsequently assembled together, each pair of co-operating end faces is in the form of two complementary or matching faces, one of which is an exact negative of the other. The elements can thus be assembled together without any seal or only with a very thin seal, e.g., using a quick-setting resin. This is the technique known as the technique of "conjugated seals."

Difficulties occur when the required civil engineering work, e.g., a bridge superstructure, has a changing pattern or course, such as a non-uniform longitudinal profile, variable horizontal curvature, e.g., an S-curve, a variable and possibly reversing super-elevation or transversal slope, or any combination of these features. The two end faces of each prefabricated element must then be spatially oriented relatively to one another in accordance with a particular program which depends on the geometric characteristics (longitudinal profile, transverse profile, plan outline) of the required work. Consequently, the factors underlying the mutual orientation of the two end faces of each of the elements concerned depend upon the local value — i.e., the value at the place where the element is to be positioned in the work — of such characteristics.

One suggestion for adjusting the mutual orientation of the two end faces of a new element to be moulded by the "conjugated joint" technique is for the previous already moulded element to be disposed in a cradle which can be oriented as required about three main axes. This process gives satisfactory results but makes it necessary to use relatively complex and expensive adjusting means and requires delicate handling.

This invention aims in general at the same target, namely adjustable mutual orientation of the two end faces of each of the moulded elements but with a simplicity and economy not previously achieved.

According to the invention, the aforesaid main longitudinal shutting bears on the previous already moulded element by way of at least three abutment devices each co-operating with a complementarily shaped locating print in the said previous element; and means are provided for preadjusting the position of the said

locating prints in dependence upon the pattern of course of the required work and of the subsequent position in said work, of the element to be moulded.

The main shutting carries auxiliary moulding members which are provided to the same number as there are abutment devices and which serve to mould in said new element the locating prints which will subsequently co-operate with the abutment members when a next element is moulded.

10 The means for preadjusting the position of the locating prints have provision for altering the position of at least one of the auxiliary moulded members relative to the said main shutting and/or for altering the position relative to the main shutting of at least one of the abutment devices, said means enabling the or each auxiliary moulding member and/or the or each abutment device to be shifted lengthwise of the element to be moulded.

15 As will be described hereinafter, if the respective shiftings of one or more of the auxiliary mould members and/or abutment devices are devised appropriately, the main longitudinal shutting can be arranged to take up a position predetermined in dependence upon the geometry of the required work (e.g., a bridge). The said work can therefore follow any three-dimensional changing pattern or course in any combination of variations of the plan curvature and/or longitudinal profile and/or superelevation profile.

20 According to another feature of the invention, which can if required be used independently, there is provided, for moulding an exposed surface of an element — i.e., a surface extending lengthwise of the element between the two end faces thereof — a deformable

25 sheet-like mould member having two sides extending transversely of the element length, which transverse sides are secured to two independent rigid supports respectively which also extend transversely, and means are provided for shifting the said rigid supports relatively to one another. As will be seen hereinafter, this feature is very useful for moulding the non-planar top surface of a bridge of variable superelevation or transversal slope.

30 The following description, together with the accompanying exemplary non-limitative drawings, will show clearly how the invention may be carried into effect.

In the drawings:

FIG. 1 is a view in longitudinal section on the line I—I of FIG. 2 of a row or series of moulded elements produced by means of a prefabrication installation according to the invention;

FIG. 2 is a view in cross-section on the line II—II of FIG. 1 of one of the moulded elements shown therein;

FIGS. 3 to 6 are views in longitudinal section which show in diagrammatic form a number of consecutive phases in the operation of one form of prefabrication installation according to the invention, FIGS. 3 and 4 being sections on the lines III—III and IV—IV respectively of FIGS. 7 and 8;

FIGS. 7 and 8 are cross-sectional views on the lines VII—VII and VIII—VIII of the installation shown in FIGS. 3 and 4;

FIG. 9 is a view in longitudinal section to an enlarged scale of part of a longitudinal main shutting equipped with an abutment device and an auxiliary mould member;

FIG. 9a is a view similar to FIG. 9, but of a variant;

FIG. 10 is a cross-sectional view on the line X—X of a detail of FIG. 9;

FIG. 11 is a view in longitudinal section on the line XI—XI of FIG. 12 of a row of moulded elements similar to the row shown in FIG. 1, except that the elements are of varying height;

FIG. 12 is a cross-sectional view on the line XII—XII of FIG. 11 of one of the moulded elements therein;

FIG. 13 is a cross-sectional view on the line XIII—X-III of FIG. 14, of another embodiment of a prefabrication installation according to the invention, of use more particularly for moulding elements of variable height;

FIGS. 14 and 15 are views in longitudinal section on the lines XIV—XIV and XV—XV respectively of the installation shown in FIG. 13.

FIG. 16 is a view in elevation, looking in the direction of an arrow XVI, of the installation of FIG. 15;

FIG. 17 is a view in longitudinal section of another embodiment of a prefabrication installation according to the invention;

FIG. 18 is a cross-sectional view on the line XVIII—XVIII of the installation of FIG. 17; and

FIGS. 19, 20 and 21 are diagrams showing three different ways of adjusting an installation according to the invention so that when subsequently assembled, the moulded elements produced by the installation form a work, such as a bridge deck or an elevated highway, having a predetermined longitudinal profile or horizontal curvature or superelevation.

Referring to FIGS. 1 and 2, a prefabricated element V_{n-1} of concrete or some like material is prepared by moulding in an installation to be described. The element has two mutually opposite end faces 1, 2 and forms part of a row or series of similar elements which are adapted to be disposed in end-to-end relationship and assembled together to form longitudinally consecutive sections of an elongated civil engineering work in which each element in the work abuts by way of one of its end faces, e.g., face 1, with the adjacent end face, e.g., face 2, of the immediately adjacent element of the work. It has been assumed in the present case that the elements are voussoirs for constructing the deck of a bridge or an elevated highway; in FIGS. 1 and 2 they are shown in the position in which they will subsequently be in the assembled work.

The longitudinal direction in an element is the direction from the one end face 1 towards the other end face 2, i.e., the horizontal direction in FIG. 1. The transversal direction in an element is thus the horizontal direction in FIG. 2.

Each element, see for example element V_{n-1} , may be a portion of box girder comprising a bottom flange 3, two webs 4 and a top flange 5. Of course, these elements do not need to be hollow and may as well, as indicated hereinbefore, be constituted by solid, i.e., non-hollow slabs. It will be assumed hereinafter that the elements are moulded in their order of subsequent assembly V_1, V_2, V_3 and so on in the finished work. The reference V_n denotes a new element which is still to be moulded, and so the immediately previous and already moulded element has the reference V_{n-1} .

As FIGS. 1 and 2 show, the element V_{n-1} has four (at least three) locating prints shown as recesses 6a, 6b, 6c, 6d which are, with advantage, distributed at the corners of a quadrilateral. The function of the locating prints will become apparent hereinafter.

FIGS. 3 to 10 shows a prefabrication installation, which as can be seen more particularly in FIG. 3, comprises, for moulding a new element V_n , a mould bounded at one end by end face 1 of the previous already moulded element V_{n-1} (which is the last element to have been moulded) the element V_n will subsequently be engaged with end face 1 of element V_{n-1} when the elements are assembled in a row or series in accordance with the "conjugated joints" technique previously referred to. The mould includes a number of outer main mould members such as 7, 8, 9 which extend, lengthwise of the element in longitudinal prolongation of the previous element V_{n-1} , or to be moulded. To simplify the drawings, only three such mould members 7, 8, 9 have been shown. But there is also provided, to mould the outer surface of flange 5 of the element, an outer mould member (not shown) of any conventional type. All said outer mould members are rigidly interconnected together to form a main longitudinal unitary shattering C, as shown in FIG. 8.

It will be assumed hereinafter that the general axis of moulding is vertical or at a slight inclination thereto, each element being cast or poured above the previous element. However, such axis can of course extend in any direction in space; for instance, each element can be cast substantially horizontally against the previous element.

By way of its other end face 2 the previous already moulded element V_{n-1} bears on a base 19 which may or may not be adjustable.

The main longitudinal shattering C abuts against or is fixed to blocks 10a, 10b, 10c, 10d which respectively carry abutment devices 11a, 11b, 11c, 11d respectively engaging with the locating prints 6a, 6b, 6c, 6d in element V_{n-1} . The abutment devices and locating prints are complementarily shaped. For example, the abutment devices may consist of pins or studs, in which case the locating prints are recesses as illustrated. However, the converse arrangement could as well be used and at least some of the abutment devices could consist of recessed portions such as notches or recesses which would engage with locating prints in the shape of raised or relief projections of the element V_{n-1} . Anchor means 12 may be used to secure the abutment devices 11a, 11b, 11c, 11d to the element V_{n-1} , as diagrammatically shown in FIG. 4.

The main longitudinal shattering C carries to the same number as there are abutment devices auxiliary mould members 13a, 13b, 13c, 13d for moulding the locating prints 6a, 6b, 6c, 6d which will subsequently co-operate with the abutment devices when the next element V_{n+1} of the series is moulded (see FIGS. 5 and 6).

The co-operating abutment devices 11a, 11b, 11c, 11d and corresponding locating prints 6a, 6b, 6c, 6d, therefore, allow to spatially locate (position and angular attitude) the main shattering C relatively to the previous element V_{n-1} already moulded. This system therefore provides a very simple procedure enabling a civil engineering work, such as a bridge, to be built, which has any evolving course or pattern, for since the position and angular attitude of the main shattering C depend upon the position of the abutment devices 11a, 11b, 11c, 11d, which position in its turn, depends upon the position of the locating prints 6a, 6b, 6c, 6d, readjusting the position of at least some of the said locating prints is a way of altering in advance the position and

angular attitude of the main shuttering C in dependence upon the pattern or course of the work to be built and the position in said work of the elements to be moulded.

With this preadjustment in view, the auxiliary mould members 13a, 13b, 13c, 13d and/or the abutment devices 11a, 11b, 11c, 11d, (or at least one of the said auxiliary mould members or abutment devices) are positionally adjustable relatively to the remainder of the main longitudinal shuttering C. To this end, and as can be seen to an enlarged scale in FIGS. 9 and 10, the shuttering C is pierced near each of the auxiliary mould members, 13a, 13b, 13c, 13d with an elongated slot 14 extending in the longitudinal direction of the shuttering C and through which a screw-threaded pin 15 extends, one end of pin 15 having a respective auxiliary mould member (shown as 13d in the drawing), while the other end co-operates with a clamping nut 16 bearing by way of a plate 17 on the main shuttering C. Consequently, the position of the auxiliary mould members such as 13d can be adjusted relatively to the shuttering C by releasing the nut 16 and shifting the pin 15 in the slot 14, along a longitudinal path.

In the embodiment shown in FIG. 9, the position of an abutment device such as 11d, relatively to the main shuttering C, is invariable; however, this feature is not essential and, instead, the feature shown in FIG. 9a can be used wherein a block 210d (analogous to block 10d in FIG. 9) is formed with a longitudinal slot 213 (similar to the slot 14 in FIG. 9) in which a screw-threaded pin 212 rigidly secured to an abutment device, such as a stud 211d, can be shifted along a longitudinal path and clamped by means of a nut 216. Also possible is an arrangement wherein the stud 211d is longitudinally shiftable whereas the auxiliary mould member 13d is in a fixed position relatively to the longitudinal shuttering C.

In the example hereinbefore described, it has been assumed that the elements $V_1, V_2, V_3, \dots$ are hollow, whereby to constitute consecutive sections of a tubular or box-girder. In that case, an inside or core shuttering is used to mould the inside surfaces of the elements. This inside shuttering, which is of any conventional type and which, in a conventional way, is moved to match with the position of the outside or main shuttering C to which it may be connected by distance pieces, has not been shown so as not to complicate the drawings. However, already set forth hereinbefore, the moulded elements do not need to be hollow and may as well be constituted by solid, non-hollow voussoirs or slabs.

In the example hereinbefore described it has been assumed that the work (such as a bridge) to be built by subsequent assembly of the moulded elements is of a constant height (the height being the dimension between the flanges 3 and 5), as shown in FIG. 1; clearly, however, the invention is not limited to this particular case and is also of use for prefabricating moulded elements of variable height, such as are shown in FIGS. 11 and 12.

A description will now be given, with reference to FIGS. 13 to 16, of an installation of use more particularly for the moulding of elements of variable height. In this case too, the main longitudinal shuttering C includes a number of main longitudinal mould members. To simplify the drawings, only three such longitudinal members 107, 108, 109 similar to the main longitudinal

mould members 7, 8, 9 previously described can be seen. The longitudinal mould members 107, 108, 109 are rigidly interconnected, but can be temporarily disengaged from one another so that the position and/or 5 inclination of the longitudinal mould members 107, and therefore the height of the element V_n to be moulded, can be varied. The longitudinal mould member 107 bears on the previously moulded element V_{n-1} by way of two abutment devices 111c, 111d carried by 10 blocks 110c, 110d and co-operating with the locating recessed prints 6c, 6d respectively. Near the zone where it bears on the element V_{n-1} , the longitudinal mould member 107 has two portions 107x and 107y which project laterally outside the webs 4 and on which 15 the longitudinal mould members 108, 109 bear, as shown in FIGS. 13, 15 and 16. The members 108, 109 also bear on the already moulded element V_{n-1} by way of abutment devices 111a, 111b carried by blocks 110a, 110b and co-operating with the locating prints 6a, 6b respectively. As in the previously described embodiment, the main shuttering C carries auxiliary mould members 113a, 113b, 113c, 113d similar to the auxiliary mould members 13a, 13b, 13c, 13d hereinbefore described. The main shuttering C is adjusted as 20 hereinbefore described with reference to FIGS. 9, 9a and 10.

FIGS. 19 to 21 show various ways in which the installation can be adjusted so that the work, such as a bridge, built upon subsequent assembly of the moulded 25 elements may have any desired evolving pattern or course. As hereinbefore described, each moulded element or voussoir V_{n-1} has four locating prints 6a, 6b, 6c, 6d which may be thought of as defining the geometric shape and angular attitude of the new element V_n to be moulded in the installation. Of these locating prints there can be seen (see FIGS. 1 and 2) two top locating prints 6a, 6b, two bottom locating prints 6c, 6d, 30 two left-hand locating prints 6a, 6d and two right-hand locating prints 6b, 6c. Like locating prints in two consecutive elements, such as V_{n-2} and V_{n-1} , are separated from one another by distance l_a, l_b, l_c, l_d respectively — i.e., $l_a = 6a - 6a$; $l_b = 6b - 6b$ and so on. The simplifying 35 assumption will be made that the required work (bridge) is of constant height. As a rule $l_a = l_b = l_c = l_d$.

If the position, for instance, of one locating print 6a is altered, the associated distance l_a varies correspondingly. It can be shown that the length L_a near the zone concerned — in the event, the top left-hand part — of the element V_n is substantially equal to the distance l_a 40 between the locating prints 6a in the previous already moulded element V_{n-1} and the penultimate already moulded element V_{n-2} . Once the distances l_a, l_b, l_c, l_d for the last two elements which have already been moulded are known, it is possible to predetermine the lengths L_a, L_b, L_c, L_d in the various zones concerned of the new element V_n to be moulded and therefore to predetermine the shape thereof and its angular attitude relative to the previous element V_{n-1} .

For instance, FIG. 19 relates to the case of a work 45 having a variable longitudinal profile. This result can be readily achieved by devising matters so that simultaneously: $l_a > l_d$ and $l_b > l_c$.

FIG. 20 relates to the case of a work with a horizontal curvature, produced by devising matters so that simultaneously: $l_a < l_b$ and $l_d < l_c$.

Finally, FIG. 21 shows how a variation of the transverse profile or superelevation can be produced by de-

vising matters so that simultaneously: $l_a > l_d$ and $l_b < l_c$. Clearly, combining the three adjustments just described will enable the work to have any evolving three-dimensional or course. Adjustment is by shifting in the longitudinal direction, to suit circumstances, one or more of the auxiliary mould members 13a, 13b, 13c, 13d and/or abutment devices 11a, 11b, 11c, 11d.

FIGS. 17 and 18 show prefabrication installation for producing moulded elements, which may be used more particularly in the case wherein said elements are intended to constitute the consecutive sections of a work, such as a bridge, having a variable superelevation (or transversal slope).

As shown in FIG. 21, the exposed surfaces, more particularly of the top flange 5 and bottom flange 3, in such a work have now planar surfaces, which may cause moulding difficulties. The same can readily be overcome if the main longitudinal mould members used for moulding the top flange and bottom flange of an element V_n to be moulded are sheet-like deformable mould members (for example of thin sheet metal), such as S or T, of which two mutually opposite sides S_1 and S_2 (or T_1 and T_2), extend transversely of the longitudinal direction of the element. The two transversal sides S_1 and S_2 of the sheet-like deformable mould member S are respectively secured to two mutually independent, rigid supports P_1 and P_2 , such as two lattice girders which also extend transversely and which can be shifted relatively to one another. Similarly, the two transversal sides T_1 and T_2 of the sheet-like deformable mould member T are respectively secured to two mutually independent, rigid supports Q_1 and Q_2 , such as two lattice girders which also extend transversely and can be shifted relatively to one another in the superelevated portion.

As will be understood, shifting of two rigid supports (say P_1 and P_2) relatively to one another entails the same shifting of the two transversal sides (S_1 and S_2) to which they are secured. The deformable sheet-like mould member (S) becomes thus deformed and non-planar, while still retaining two straight sides (S_1 and S_2), as desired for moulding the non-planar surface shown in FIG. 21.

The lattice girders P_1 and Q_1 , P_2 and Q_2 are interconnected by way of rods 330, 331 so that the mould members S, T are rigidly interconnected to form a main shuttering C which bears on the previously moulded element V_{n-1} by way of four abutment devices 311a, 311b, 311c, 311d, respectively carried by four blocks 310a, 310b, 310c, 310d and co-operating with the locating prints 6a, 6b, 6c, 6d respectively. As previously described, the main shuttering C carries auxiliary mould members 313a, 313b, 313c, 313d which — except as regards the place of the mould members 313a, 313b — are similar to the auxiliary mould members 13a, 13b, 13c, 13d previously described. The main shuttering C is adjusted as hereinbefore described with reference to FIGS. 9, 9a and 10.

Clearly, the embodiments described are only examples and can be modified, inter alia by the substitution of technical equivalents, without departure from the scope of the invention as defined in the appended claims.

I claim:

1. An installation for prefabricating in succession a series of consecutive sections of an elongated civil engineering work, each section consisting of a precast

molded element of concrete-like material having two mutually opposite end-faces and a side surface extending between said two end-faces in a longitudinal direction from one to the other of said two end faces, said installation being designed for molding a new element of the series against an end-face of an immediately previous, already-molded element of the series, and comprising:

a number of longitudinal main mold members at least some of which are interconnected together to form a unitary main longitudinal shuttering projecting in longitudinal prolongation of said previous, already-molded element, said main shuttering having two longitudinally spaced end regions including a first end-region which is proximal with respect to said previous element and a second end-region which is distant with respect thereto;

means interconnecting said main shuttering and said previous, already molded element for accurately positioning said main shuttering with respect to said previous element, said means including at least three mutually spaced, non-aligned abutment devices near said proximal end region of said main shuttering and each engaging with a respective complementarily shaped locating print formed in the side surface of said previous, already molded element; and

at least three auxiliary mold members located at said distant end region of said main shuttering, each in respective longitudinal alignment with a corresponding one of the said abutment devices for molding in said new element of said series, locating prints for subsequent engagement with said abutment devices during the molding of the next element of the series; wherein the improvement comprises:

at least one rectilinear, elongated guideway fixed in position with respect to said main longitudinal shuttering and extending in the longitudinal direction of said shuttering at said distant end region thereof in longitudinal alignment with one of the said abutment devices;

a slide-block integral with said one of said auxiliary mold members which corresponds to said one abutment device and slidable along said longitudinal guideway whereby said one auxiliary mold member is adjustable along a longitudinal path with respect to said main longitudinal shuttering; and

clamping means for locking said adjustable auxiliary mold member in any preselected position along said longitudinal path.

2. An installation for prefabricating in succession a series of consecutive sections of an elongated civil engineering work, each section consisting of a precast molded element of concrete-like material having two mutually opposite end-faces and a side surface extending between said two end-faces in a longitudinal direction from one to the other of said two end faces, said installation being designed for molding a new element of the series against an end-face of an immediately previous, already-molded element of the series, and comprising:

a number of longitudinal main mold members at least some of which are interconnected together to form a unitary main longitudinal shuttering projecting in longitudinal prolongation of said previous, already-

molded element, said main shuttering having two longitudinally spaced end regions including a first end-region which is proximal with respect to said previous element and a second end-region which is distant with respect thereto;

means interconnecting said main shuttering and said previous, already-molded element for accurately positioning said main shuttering with respect to said previous element, said means including at least three mutually spaced, non-aligned abutment devices at said proximal end-region of said main shuttering and each engaging with a respective complementarily shaped locating print formed in the side surface of said previous, already molded element; and

at least three auxiliary mold members located at said distant end-region of said main shuttering, each in respective longitudinal alignment with a corresponding one of said abutment devices for molding in said new element of said series, locating prints

5

10

15

20

for subsequent engagement with said abutment devices during the molding of the next element of the series; wherein the improvement comprises:

at least one rectilinear elongated guideway fixed in position with respect to said main longitudinal shuttering and extending in the longitudinal direction of said shuttering near said proximal end region thereof in longitudinal alignment with one of said auxiliary mold members;

a slide-block integral with one of said abutment devices which corresponds to said one auxiliary mold member, and slidable along said longitudinal guideway whereby said one abutment device is adjustable along a longitudinal path with respect to said main longitudinal shuttering; and clamping means for locking said adjustable abutment device in any preselected position along said longitudinal path.
